United States Patent Office

Des. 196,076
Patented Aug. 20, 1963

196,076

BOTTLE

Martin Schnur, Shorthills, N.J., assignor to Celanese Corporation of America, New York, N.Y., a corporation of Delaware

Filed Dec. 6, 1962, Ser. No. 72,742

Term of patent 14 years

(Cl. D58—6)

FIG. 1 is a side elevation of a bottle showing my new design.

FIG. 2 is a rear elevation thereof.

FIG. 3 is a front elevation thereof.

FIG. 4 is a plan view thereof.

The side of the bottle not appearing in the views corresponds to that side shown in FIG. 1.

I claim:

The ornamental design for a bottle, as shown and described.
